UNITED STATES PATENT OFFICE

155,889

DESIGN FOR A SYRINGE

Arthur R. Gow, Hamden, and Charles T. Manville, Woodbury, Conn., assignors to The Seamless Rubber Company, New Haven, Conn., a corporation of Connecticut

Application November 4, 1948, Serial No. 149,471

Term of patent 14 years

(Cl. D83—1)

To all whom it may concern:

Be it known that we, Arthur R. Gow and Charles T. Manville, residing, respectively, in Hamden, county of New Haven, and Woodbury, county of Litchfield, State of Connecticut, have invented a new, original, and ornamental Design for a Syringe, of which the following is a specification, reference being had to the accompanying drawing, forming part thereof, in which

Fig. 1 is a side elevation of a syringe, showing our new design; and

Fig. 2 is a top plan view of the syringe.

We claim:

The ornamental design for a syringe, substantially as shown.

ARTHUR R. GOW.
CHARLES T. MANVILLE.
